JAMES R. COLE.

INVENTOR

BY Tom G. Bowman.

ATTORNEY

UNITED STATES PATENT OFFICE

JAMES R. COLE, OF TULSA, OKLAHOMA

DEFLECTOR

Application filed October 7, 1929. Serial No. 397,822.

My invention relates to a deflector and more particularly to a wheel adapted to change the direction of motion of a flexible reciprocating power element.

- 5 Fairleaders and self aligning pulleys and the like are not suitable for use with my invention as set forth in my application entitled a Power unit, filed Nov. 11, 1927, Serial No. 232,679 and it is the object of this invention 10 to create a deflecting sheave wheel device which will not only function perfectly in relationship with the above referred to power unit but which may be utilized in other suitable installations.
- 15 My device is adapted to be mounted directly below the lowermost point through which a crank pin passes and a flexible power element leads from a wrist pin iron or plate encircling the crank or wrist pin through a 20 sheave wheel pivotally mounted on the base of my device. The base has a boss which is adapted to be revolvably mounted in a foundation and thus proper alignment of the device may be obtained. A sheave wheel is rotatably mounted in a frame and this frame is pivoted onto the base. The inner edge of the 25 sheave wheel is directly above the axis or center line of the boss. The bottom edge of the sheave wheel is in alignment with the 30 pivot mounting of the frame. The power element may consist of a chain or a cable. This power element leads from the well pumping unit at the well to the rotating wrist or crank pin. The element passes through or around 35 the deflector unit and thus has its direction of pull changed from a horizontal plane to a vertical plane or vice versa.

One advantage of my invention is that I mount my pulley or sheave wheel with its bottom edge substantially in line with the axis about which the frame swivels or swings and thus the power element remains in exact alignment at all times.

The exact alignment, supra, is obtained by 45 another advantage or novel feature of my invention. This consists of forming the bearing or connection between the frame and its base so that a central aperture is allowed to remain in alignment with the axis thereof.

50 Hence, by sighting through this hollow "tele-

scope" one may adjust the base about its boss until it is exactly in line. Then it may be fixed in position.

This boss serves as a sort of guiding means. That is, the boss is placed under the base directly below the rim of the sheave wheel at its inner side. Before positioning the base or base plate a point is obtained directly below the center of the wrist pin when it is in its center position and at this point a recess 55 may be formed for the mounting of the boss therein. When this is done the inner edge of the sheave wheel will be in line with a vertical plane bisecting the crank or wrist pin transversely and will remain so as the 60 bearing between the frame and the base is in perpendicular relationship to this plane.

Another advantage resides in my adjustable stop means such as bolts threaded into the base plate which prevents the frame from 65 excessive movement. Also, these bolts prevent the frame from falling down sideways when the tension on the lower element ceases or slackens. Furthermore, these adjusting bolts are an aid when transporting the device 70 since they may be tightened so as to hold all parts in rigid relationship.

Still another advantage lies in my means for preventing the chain power element from hanging or catching on the edges of the guard 75 which is usually used with the sheave wheel. The rivets or bolts in a sprocket chain are prone to hit and get hung up on the side edges of the guard and especially so when the well has been disconnected from the far end of the power element, and I provide curved 80 means which guides the protruding bolt heads or rivets past the abrupt edges of the guard.

Other objects and advantages reside in the special construction, combination and arrangement of the various elements forming the invention as more fully hereinafter described and claimed, reference being had to the accompanying drawings forming part 85 hereof, wherein;

Figure 1 is a side view of a modified form 90 of my invention.

Figure 2 is an end view of Figure 1, the dotted lines showing the position which the 95 frame may assume.

Figure 3 is a top or plan view of the modified form shown in Figures 1 and 2.

Figure 4 is a side view of the preferred form of my invention.

5 Figure 5 is a view in cross section taken along the line V—V of Figure 4.

Figure 6 is a view looking in the direction of the arrow —A— shown in Figure 4.

Figure 7 is a view of the bottom of the base 10 plate.

Similar numerals designate similar parts throughout the several views.

In the drawings —10— indicates the base or base plate which is held to a foundation 15 (not shown) by means of bolts —11—. The base plate —10— has upstanding lugs or ears —12— and —13— for supporting the journal or pipe —14—.

A yoke or frame member —15— has a bearing —16—, which coacts with the journal —14—, and is bifurcated as at 17. A sprocket or wheel —19— is revolvably mounted between the two arms of the bifurcation by means of the pin —18— and a flexible 25 power element or chain —20— is trained thereover as clearly shown in Figure 1.

A guard —22— is fastened to the frame and moves therewith. This guard has two carved members —23— and —24— which 30 are rigid therewith as shown in Figure 2. These members keep the projecting parts of the chain from catching on the edges of the guard when the chain is slackened.

Studs —25— and —26— are threadedly 35 engaged in the bosses —27— and —28— and serve as stops to limit the arcuate movement of the frame member —15— and its appurtenances.

Referring now to the preferred modification shown in Figures 4-7, inclusive, which operates practically identical with the modification just described, —50— designates a base or base plate having ears or lugs —51— and —52— on its top side and a cylindrical boss —53— on its bottom side. The boss —53— is adapted to revolvably seat in the recess —48— in the foundation —49— and thus the base may rotate. Slots —54—, —55—, —56—, and —57— are circumposed about the axis of the boss and bolts —58—, held rigid in the foundation, pass therethrough and provide means for clamping the base plate in its aligned position.

45 A hollow journal or pipe —60— is supported by ears —51— and —52—, integral with the base plate, and a yoke or fork —64— is journalled thereon. Ears —66— and —67— extend from the yoke and bolts —68— are threaded therethrough and held therein by lock nuts —69—. Thus the arcuate movement of the yoke or frame may be limited or adjusted.

50 A sheave or grooved pulley —80— is rotatably mounted in the yoke or frame by means

of a pin —81— and a power element —82— rides therein.

A guard —70—, having guide members —71—, guides the power transmitting element, when slack, and is fastened to the frame as at —72—. A lower guard —73— is also fastened to the yoke or frame.

Small ribs —91— and —92— see Figure 4, are provided internally of the hollow pipe —60— as an aid to sighting therethrough.

The operation will be readily understood when this case is considered with the parent case referred to.

In both modifications the power element reciprocates in its horizontal plane and travels in a circle in the vertical plane. Hence, the device is allowed to rotate about the incoming horizontal power element. Thus the rotary motion, due to the wrist pin traveling in a circle, is taken care of and proper alignment is obtained at all times. Increased efficiency is the result.

While I have described complete embodiments of my invention I do not wish to be limited to the particular constructions shown, my invention being in fact limited solely by the attached claims.

1. A device adapted to change the direction of motion of a flexible power element from a straight line reciprocating motion to a circular motion in a plane at right angles to the straight line reciprocating motion comprised of a base, a boss thereon, means to support the base, said means having a recess to revolvably mount the boss, means rigid with the first mentioned means to clamp the base in a selected position; ears on the base, a hollow journal mounted on or in said ears, a frame having a bearing adapted to revolve on said journal, said frame being bifurcated at its upper end; a sheave wheel adapted to guide the flexible power element, and means to revolvably mount the sheave wheel so that one tangent from its rim will align with the axis of said boss and another tangent will align with said hollow journal means.

2. A direction changing device for a flexible power transmitting element comprised of a base having a cylindrical shaped boss, a foundation having a recess adapted to rotatably receive the boss, means to hold the base in any selected position; a frame, means to pivotally mount the frame on the base; stop means to limit the arcuate movement of the frame; a wheel adapted to engage said flexible power element, and with said wheel revolvably supported by the frame so that it will rotate about an axis perpendicular to the plane of rotation of the frame and also have a tangent in alignment with the axis of the cylindrical shaped boss.

3. A unit comprised of a base, a hollow shaft, means to mount the hollow shaft on the base, a wheel, and means to mount

the wheel so as to swing bodily about the hollow shaft at a tangent from the rim of the wheel, and means on the base in alignment with a tangent from the rim of the wheel 5 whereby the base may be swung thereabout.

4. A device adapted to change the direction of motion of a flexible power element comprised of a base, a frame, means for mounting said frame on the base, a wheel, 10 means for revolvably mounting said wheel in said frame, said first mentioned means having an aperture through its axis and said second means supporting the wheel so that a tangent therefrom will be in alignment with 15 the aperture.

5. An aligning device having a base, a wheel, means revolvably mount the wheel so that it may be moved bodily about a tangent thereto, and additional means to pivotally 20 support the base about an axis substantially in alignment with a tangent to said wheel, said means for mounting the wheel having an aperture in alignment with its axis.

6. A direction changing device for a tensioned flexible power element comprised of a pivoted frame, a wheel therein, means to limit the movement of the frame, and means on the frame to contact with and guide the power element when said element is not under strain.

7. In a device having a frame and a revolving wheel therein, said structure being bodily movable about an axis and flexible means under tension passing partly around the 25 wheel, the combination of a guard rigid with the frame and means mounted on said frame and adapted to prevent said flexible means from catching on said guard when the tension is removed from said flexible means 40 and when the device is laying out of the plane of its working position and while the flexible means remains connected to the source of power actuating it.

8. A direction changing device for a flexible power transmitting element comprised of a base having a boss, a foundation having a recess adapted to revolvably receive the boss, means to hold the base in any selected position; a frame, means to mount the frame on 50 the base; a wheel adapted to receive the transmitting element and means to mount the wheel so that one tangent to its rim will be in alignment with the center of the boss.

55 9. A direction changing device for a flexible power transmitting element, comprising a base, a plate having a connection with the base so as to be capable of swinging movement in a horizontal plane, means connecting the plate to the base to normally prevent such swinging movement, brackets on the plate, a pin mounted in the brackets, a yoke journalled on the pin, and a wheel journalled in the yoke, said wheel and pin laying in the 65 same plane, the axis of the pin being coinci-

dent with one tangent to the wheel and the axis of the first connection being coincident with a second tangent to the wheel, and the tangents being at right angles to each other.

In testimony whereof I affix my signature. 70
